PROCESS AND APPARATUS FOR STABILIZING CRUDE PETROLEUM

Filed Aug. 19, 1926

FREDERICK B. BIMEL Inventor

By Attorney *Attaway*

UNITED STATES PATENT OFFICE

FREDERICK B. BIMEL, OF WESTFIELD, NEW JERSEY, ASSIGNOR TO STANDARD OIL DEVELOPMENT COMPANY, A CORPORATION OF DELAWARE

PROCESS AND APPARATUS FOR STABILIZING CRUDE PETROLEUM

Application filed August 19, 1926. Serial No. 130,167.

The present invention relates primarily to the prevention or reduction of losses by evaporation of crude oils during transportation and storage. A method of reducing losses of gasoline fractions from crude petroleum is provided whereby the gases in solution in the oil are removed by rectifying means and the stripped oil can then be stored or transported without the losses of gasoline normally attending the escape of such dissolved gas.

It is well known that crude petroleum as it is obtained from flowing or pumping wells contains dissolved gases, and that upon the gas escaping, normally liquid products are carried away with the gas. My invention includes the use of a rectifying column in which dissolved gases are removed with the least possible quantity of normally liquid material. In this manner the quantity of gasoline evaporated will be less than when the gas escapes by simple distillation as from a vent tank, and consequently subsequent loss by evaporation during transportation and storage will be reduced. In other words, the crude oil is stabilized by removing from it those gases that are incondensable in a pure state under ordinary atmospheric conditions of temperature and pressure, the presence of which normally gaseous constituents tends to cause excessive loss of valuable less volatile materials.

My invention will be fully understood from the following description and the drawing which is a semi-diagrammatic view in elevation of the preferred form of the apparatus constructed according to my invention.

In the drawing a feed line 1 carries crude oil fresh from the wells to a preheater 2 provided to raise the temperature of the oil before it is introduced into a rectifying or stripping tower 3 which is preferably furnished with bell-cap plates 4 and overflow pipes 5 for passage of vapor and liquid respectively. A heating coil 6 is located in the base of the tower 3, from which the stripped oil flows to pump 8 and to a cooler 9.

A cooling coil 7 is located at the top of the tower to condense gasoline which may be vaporized, and a line 10 provided with a con-

densate drum 10^a conducts effluent vapors to vacuum pump 11 and to the separator drum 12. Vapor from 12 is compressed in compressor 13 and is discharged into separator drum 14, from which the gas, deprived of its more readily condensable fractions, is sent by line 15 to boilers as fuel or to gas mains. Condensate drums 12 and 14 are connected by pipes to pump 16 so that each condensate may be withdrawn separately, or either or both may be mixed with the cold stripped oil flowing from cooler 9 to storage or pipe lines for transportation.

In the operation of my process it has been found that oil from different sources requires different conditions of pressure and temperature. The best results are ordinarily obtained with vacua of 10 to 28 inches mercury corresponding to absolute pressures of approximately 2 to 20 inches mercury and a preheat temperature of 100 to 250° F. for the crude oil. The temperature at the top of the tower will range from 75 to 200° F., and at the base of the tower from 150 to 300° F. It will be understood that these temperatures may vary considerably with the heating steam pressure available and the cooling water temperature. It is advantageous to have the oil flowing from the base of the tower about 50 to 100° F. higher than the entering crude, and effluent gases will be 30 to 75° F. lower than the crude. It is advantageous to maintain the flow of oil as constant as possible, and automatic control devices are preferred but not required.

There are several modifications of the above mentioned apparatus which lie within the scope of my invention. The tower 3 may be packed with broken coke, stones, or contact rings as is well known in the art. The preheater 2 may be a heat exchanger, heating the fresh crude at the expense of the heat of the oil flowing from tower 3 with obvious advantages. With careful rectification it should not be necessary to have the compressor 13, although it is preferred; any gasoline expelled may be recovered by absorption in oil or on charcoal, as is well known. Cooling at the top of tower 3 is preferably accomplished with cold water, but in certain

circumstances, where the crude contains large quantities of gas, the cooling may be accomplished by allowing part of the liquid from drums 12 and 14 to expand into the tower as is well known in the art.

It is generally the case that vacuum is advantageous but for certain crudes which contain excessively large quantities of gaseous materials, rectification may be accomplished under atmospheric or even superatmospheric pressure.

My invention is not to be considered limited by any theory which may be offered as an explanation of the operation of the process but only by the appended claims, in which I intend to claim all novelty inherent in my invention and allowable in view of the prior art.

I claim:

- 20 1. Apparatus of the character described, comprising a rectifier for crude petroleum, heating means in the lower portion of the rectifier, separate means for removing and cooling liquids and gases from the rectifier, means for compressing said gases, and means for returning condensate from said compression means to the cooled oil flowing from the rectifier.
- 30 2. A process for stabilizing crude petroleum, comprising rectifying the petroleum under reduced pressure and at a temperature above that of the atmosphere, separately removing liquid and gas containing vapor, cooling said liquid, compressing the gas to condense normally liquid constituents therefrom, and returning the condensate to the cooled liquid.
- 35 3. A process for stabilizing crude petroleum, comprising rectifying the petroleum, separately removing liquid and gas containing vapor, cooling said liquid, recovering normally liquid constituents from the gas containing vapor, and returning said constituents to the cooled liquid.
- 40 4. A process according to claim 3, in which the rectification is carried out at a temperature below 300° F.
- 45 5. A process for stabilizing crude petroleum, comprising rectifying the petroleum at a temperature above that of the atmosphere, separately removing liquid and gas containing light normally liquid hydrocarbons, cooling said liquid, and admixing therewith light normally liquid hydrocarbons freed from the gas.

FREDERICK B. BIMEL.
